P. ZULIANI

INSTRUMENT FOR DRAWING ELLIPSES

Filed May 21, 1923

FIG. 1.

FIG. 2.

By: *Percy H. Moore*
Atty. *Pietro Juliani*

Patented Mar. 9, 1926.

1,575,889

UNITED STATES PATENT OFFICE.

PIETRO ZULIANI, OF LONATO, ITALY.

INSTRUMENT FOR DRAWING ELLIPSES.

Application filed May 21, 1923. Serial No. 640,525.

To all whom it may concern:

Be it known that I, PIETRO ZULIANI, engineer, citizen of the Kingdom of Italy, residing at Lonato, Cenedella No. 157, in the 5 Province of Brescia, Italy, have invented certain new and useful Improvements in and Relating to an Instrument for Drawing Ellipses, of which the following is a specification.

10 This invention relates to an instrument for drawing ellipses and similar curves as projection of a circle or parts thereof.

The object of the invention is to provide an instrument of the character described 15 which is simple and economical in construction and particularly adapted to draw ellipses or oval curves when the two axis of said curves are given.

The invention consists broadly in an embodiment of a frame revolving upon a spindle, the latter having adjustable thereon a guide which is formed of two independent semi-circular plates mounted upon a common axis and against which a bar pivotally connected at the lower end of the frame is adapted to bear, said bar being maintained 20 constantly in such a position by a second bar under resilient tension and which is provided at its lower end with a suitable drawing pen or the like, this last said bar being pivotally connected to the upper portion of said frame.

The invention will be fully described with reference to the annexed drawing, in which:—

35 Figure 1 is a side view of the instrument, and

Figure 2 is a view at right angles to that of Figure 1.

Referring to the accompanying drawing 40 in detail, wherein like reference characters denote corresponding parts throughout the several views, the instrument consists of a frame 1 formed of suitable tubing and provided with an upper curved portion which terminates into a horizontally disposed portion 2 and a downwardly projecting leg 3.

The frame 1, thus described, has passing 45 through the leg 3 a spindle 4 upon which the frame 1 is mounted for rotary movement, the latter being provided with a suitable bearing 6 and 7 at the upper and lower portions of the leg 3. The upper end portion of the spindle bears upon a bearing block 5 mounted within the horizontally disposed 55 portion 2. The lower end portion of the

spindle 4 is pivotally connected to a foot piece 8, the same having points 9 for maintaining the instrument in a desired point when using.

60 Mounted upon the spindle 4 is a guide element formed of a pair of semi-circular plates 10 connected together upon a common axis, the intermediate portion of which is provided with a suitable opening through which the spindle passes. The plates 10 have pivotally connected thereto arms 12 which are further pivotally connected to a sliding piece 11 mounted upon the spindle 4 and maintained in a desired position by a thumb screw 13. From this construction it will be noted that as the sliding piece 11 is moved with respect to the axis of the plates 10 their inclination will be accordingly changed. The plates 10 are further provided with extensions 14 the end portions of each pair having passing therethrough the ends of pins 22 carried by a block 23 adjustable upon the spindle 4 and maintained thereon in a fixed relation by a set screw 24.

70 The end portion of the frame section 2 is provided with a channel 16 in which is movable the free end portion of a bar 19 the lower end of which is pivotally connected adjacent the end of the leg portion 3, said bar being adapted to bear upon the edge of the plates 10 in a manner hereinafter described. The bar 19 is provided with an elongated slot 19', the purpose of which will 75 hereinafter be described.

80 The horizontally disposed portion 2, of the frame 1, has pivotally connected to its end a bar 15 which does not fall within the same vertical plane with the bar 19. As disclosed in the drawing it will be noted that the bar 15 is caused to swing inward toward the base 8 by a suitable tension spring 16, one end of which is connected to the frame portion 2 while the other end is connected to the bar 15.

85 In order to maintain the bar 15 in such a position that it will be acted upon by the bar 19, as the latter follows the periphery of the plates 10, I have provided upon the bar 15 a sliding piece 17 which carries a projection 18 adapted to be received within the slot 19' of the bar 19, the sliding piece 17 being adjustable upon the bar 15 and secured in a desired point by a thumb screw 20. The lower end of the bar 15 is provided 90 with a suitable scribing element 21.

105 In order to revolve the frame 1 about the

spindle 4, the former has secured to its portion 2, and over the bearing block 5, a turning piece 22.

The method of using the instrument is as follows:

Pin the points 9 on the shorter given axis, care being taken to center the middle point on the given center of the curve. Then turn the frame by means of the finger piece 22 10 until the axis of the split guide plate falls within a plane common to that of the upper portion of the frame. The sliding piece 17 is next adjusted to make the end of the pen 21 coincide with the end of the longer axis 15 of the curve, and the frame is then turned 90° to bring the plane of the frame in such a position that the end of the pen will be on the minor axis of the curve. The operator then adjusts the sliding piece 11 to 20 bring the end of the pen coincident with the end of the minor axis.

The instrument as thus described is prepared to draw the desirable curve, which will be traced as it is done with the ordinary 25 compass.

Having thus described my invention, what I claim as new, and desire to secure by Letters Patent, is:—

1. An instrument of the class described including a spindle, a frame pivoted to and movable about said spindle and having a marking element connected thereto, a pair

of semi-circular plates, means pivoting said plates on a common axis, said means having therein an opening through which the 35 spindle passes, means connected to said plates and slidable upon said spindle whereby said plates are adapted to assume various angles of inclination, a bar connected to said frame and means for resiliently holding 40 said bar against the periphery of said plates during the movement of the frame about the spindle, said bar being adapted to control the movement of said marking element.

2. An instrument of the class described including a spindle, a frame pivoted to and rotatable upon said spindle, a marking element pivotally connected to said frame, a pair of semi-circular plates, means pivoting said plates on a common axis, said means having the spindle passing therethrough, means connected to said plates and slidable upon said spindle for moving the plates into various angles of inclination, a bar movable with respect to said frame and means for holding the same against the periphery of 55 said plates when moved thereabout, said bar being adapted to control the movement of said marking element when the frame is moved about the spindle.

In testimony whereof I affixed my signature.

PIETRO ZULIANI.
